Primary Examiner — Michael A. Pratt*Assistant Examiner* — Michelle E Wilson(74) *Attorney, Agent, or Firm* — Harness, Dickey & Pierce, PLC(57) **CLAIM**

The ornamental design for a polishing pad, as shown and described.

DESCRIPTION

FIG. 1 is a perspective view of the polishing pad in accordance with the present invention, with an enlarged portion exploded out therefrom;

FIG. 2 is a workpiece-facing plan view of the polishing pad shown in FIG. 1, with an enlarged portion exploded out therefrom;

FIG. 3 is an opposite plan view from that of FIG. 2 of the polishing pad shown in FIG. 1; and,

FIG. 4 is a side elevation of the polishing pad shown in FIG. 1.

The broken lines form no part of the claimed design. The pattern designations shown in the figures are not intended to claim the specific patterns but are instead intended to claim that the pattern in the outer ring (e.g., FIGS. 1 and 2) is different than the fibrous pattern in the center and backside of the pad (e.g., FIGS. 1-3).
